UNITED STATES PATENT OFFICE.

JAMES THOMPSON, OF VEVAY, INDIANA.

IMPROVEMENT IN CHURNS.

Specification forming part of Letters Patent No. 42,029, dated March 22, 1864.

To all whom it may concern:

Be it known that I, JAMES THOMPSON, of Vevay, Switzerland county, Indiana, have invented a new and useful Improvement in Churns; and I do hereby declare the following to be a full, clear, and exact description thereof, reference being had to the accompanying drawings, making part of this specification.

Figure 1 is a transverse section of my improved churn. Fig. 2 is a longitudinal section thereof. Fig. 3 shows the driving shaft and accessories detached.

The wooden bottom A' of the tub A and a false bottom, B, of zinc or other suitable metal, inclose between them a chamber, C, for the reception of hot or cold water. It is necessary that the zinc bottom B should fit the ends and sides of the tub perfectly water-tight, and yet be readily removable, the zinc being liable to wear out more quickly than the other portions. This twofold desideratum is secured by the following construction: The zinc is curved slightly downward in the middle, so as to be parallel, or nearly so, with the curved wooden bottom A', and is flanged at the edges b b' to occupy grooves in the ends of the tub, its ends a a' occupying grooves in the tub sides.

D is a cleat, which, being screwed to the tub's side, secures the sheet of zinc firmly in place. The tempering-chamber C is closed by a cover, e. The mouth of the churn is closed by a cover, F, having the represented parallel beveled edges f'.

My dasher is constructed as follows: The hub G is in the form of a prism of eight sides, for attachment of that number of blades, H, chamfered in the manner represented at their edges 1 2 3, so as, when revolved in direction of arrow, to act to divide the milk, and to carry down air into it, and to create a violent disruption of its cells by the concussion which the milk suffers in the receding angles or corners 4 of the dasher. One end of the hub G rests in a socket, I, in the tub end. The other end of the hub is provided with a square socket, L, which receives the square end m of a shaft, M, capable of being slid in or out of the hub. The outer extremity, m', of the shaft M is also square, to receive a crank, O. The shaft M occupies a stuffing-box, P, in the tub-end, said box being packed with tow or other suitable

material. A washer, Q, and cap R confine the packing within the box P. The part of the shaft M which traverses the box P is of somewhat larger diameter than the part outside of the box, so as to leave a shoulder, 5. The outer end of the shaft M journals in a hanger or bridge, S, between which and the shoulder a sufficient interval is provided for the peculiarly-formed key T, by which the shaft is retained in its working position. The key T is an oblong ring, broad at one end and narrow at the other. The narrow end, being up, acts to hold the shaft to its work, while, on the other hand, the broad end, being uppermost, enables the shaft M to be retracted sufficiently to liberate the dasher for removal from the tub. To facilitate such removal the tub-end is channeled out, 6, on its inner face. An aperture, V, enables the withdrawal or insertion of the dasher.

It will be perceived that the double bottom formed of wood or other slow conductor, in all parts which are exposed to the external air, and of metal where it touches the milk, acts to preserve the heating or cooling influence, and appropriate it wholly to the milk.

It is found that the part 7 of the dasher nearest to the tub-side acts to rapidly form the butter, while the more open space 8, being comparatively quiescent, permits the eliminated butter to gather together. The butter being "come" is very quickly gathered in the open space 8 by a few reverse turns of the dasher. The butter having been gathered, the key T is reversed, and the shaft M having been retracted, the dasher may be lifted out, leaving the churning in the tub. The hub may have a socket at each end, so as to be reversible when desired. Wings V may be provided on the ends of the dasher to expedite the churning action.

The dasher may consist of a greater or less number of blades than here illustrated, and may be formed of a single block of wood.

It will be seen that the sharpened blades of the dasher will enter the milk with a cutting action, which, while demanding only a slight exertion on the part of the operator, produces a violent agitation of the milk.

I claim herein as new and of my invention—

1. The tempering-chamber C in the described combination with the movable metallic floor

B, wooden bottom A', and cover c, all constructed, arranged, and applied in the manner and for the purposes herein specified.

2. The manner of attaching and detaching the metallic floor B by means of the devices a a' b b' D, as herein shown and explained.

3. The dasher, consisting of an octagonal or other prismatic shaft, G, with chambered straight-sided boards H H H, applied one to each face of the shaft and overlapping each other, all as represented and described.

4. The combination, with the retractible

shaft M, bridge S, and stuffing-box P, of the tapering ring T, formed and applied in the manner and for the objects specified.

5. The arrangement of a single rotary dasher, G H, journaled eccentrically within the tub, as described.

In testimony of which invention I hereunto set my hand.

JAMES THOMPSON.
